WIRE REEL

Rudolph Prang, Hurdsfield, N. Dak.

Application August 15, 1940, Serial No. 352,791

3 Claims. (Cl. 242—113)

This invention relates to a reel for winding and unwinding wire and more particularly for winding and unwinding barbed wire.

It is a primary aim of the invention to provide a reel of simple construction adapted to be removably and rotatably mounted on a rod or pipe and having means whereby a roll of wire may be readily removed therefrom, after being wound thereon or whereby a roll of wire may be readily applied thereto for unwinding the roll.

Still another aim of the invention is to provide a reel having means for varying the diameter thereof for adapting it to rolls of wire having openings of different sizes and more particularly to permit placing a roll of wire on the reel which has been removed therefrom for some time so that the opening, in the roll, has become restricted so that it will not fit a reel as large in diameter as the one on which it was wound.

Other objects and advantages of the invention will hereinafter become more fully apparent from the following description of the drawing, which illustrates a preferred embodiment thereof, and wherein:

Figure 1 is a side elevational view showing the reel applied to a pipe or rod attached to the rear end of a truck body,

Figure 2 is an end view in elevation of the reel,

Figure 3 is a vertical sectional view, on an enlarged scale, taken substantially along the plane of the line 3—3 of Figure 2,

Figure 4 is an enlarged sectional view taken substantially along the plane of the line 4—4 of Figure 2,

Figure 5 is an enlarged sectional view taken substantially along the plane of the line 5—5 of Figure 1.

Referring more particularly to the drawing, wherein like reference characters designate like or corresponding parts throughout the different views, 10 designates generally a portion of the rear end of a truck body to which is connected a plurality of eyebolts 11 which are disposed in spaced apart, aligned relationship relatively to one another for receiving a rod or pipe 12, one end of which extends beyond the body 10.

A winding and unwinding reel, designated generally 13, includes a hub 14 which is removably and rotatably mounted on the extended end of the pipe or rod 12 and which is provided with an annular flange 15. The flange 15 is provided on one side thereof with a plurality of pairs of radially extending ribs 16. The ribs 16 of each of the pairs are disposed in spaced apart sub-

stantially parallel relationship. A bar 17 has one end disposed in each of the pairs of ribs 16. Each of the bars 17 is connected to the flange 15 by means of a bolt and nut fastening 18 which extends through aligned openings 19 in the flange 15 and bar 17. The fastenings 18 combine with the ribs 16 to prevent the bars 17 from turning relatively to the flange 15. As best seen in Figure 2, the bars 17 project radially from the flange 15 and are disposed substantially equal distances apart and are preferably four in number to form a cross.

The bars 17, adjacent their secured ends, are provided with longitudinally spaced, correspondingly positioned openings 20. Four corresponding rods 21 are each provided with a threaded end 22 to loosely engage a corresponding opening 20. The ends 22 each carry a pair of nuts 23 which are adapted to be disposed, one on each side of a bar 17 for clamping the rod 21 thereto. The opposite, free ends 24 of the rods 21 are curved to extend outwardly to form one end of the reel 13, the opposite end of which is formed by the outer ends of the bars 17, and the intermediate portion of which is formed by the portions of the rods 21 between the threaded ends 22 and the curved ends 24.

One of the bars 17 is provided with an opening 25 adjacent its outer end to receive the shank end of a bolt 26 on the shank of which is mounted a sleeve 27 which is disposed between said bar 17 and the head of the bolt. A nut 28 is attached to the threaded shank end of the bolt 26 to detachably connect the bolt and sleeve to said bar 17. The sleeve 27 is turnably mounted on the bolt 26 and combines therewith to form a handle, designated generally 29, which combines with the bar 17 to which it is connected to form a crank for revolving the reel 13.

From the foregoing it will be obvious that the reel 13 may be readily removed from or applied to the extended end of a pipe or rod 12. For winding wire or barbed wire on the reel 13, the rods 21 are positioned in the outer openings 20 and clamped by their nuts 23 so that their curved ends 24 will extend outwardly, as illustrated in Figures 1 and 3. With the reel thus assembled it will be obvious that while barbed wire may be readily wound thereon to form a roll after which the outer nuts 23 may be loosened to permit the rods 21 to be turned relatively to the bars 17 so that their curved ends 24 will be directed inwardly to permit the roll to be removed from the reel 13 after the reel has been removed from the rod or pipe 12. A roll of wire

may be applied to the reel 13 when the ends 24 are turned inwardly after which the rods 21 are turned to swing the ends 24 outwardly and then clamped in this position by tightening the outer nuts 23. The reel 13 may be then applied to the rod or pipe 12 and turned by the handle 29 for unwinding the roll of wire therefrom. After a roll of wire has been left standing for a period the opening thereof will contract so that it will be too small to engage the rods 21 when they are in the same positions as when the roll was wound thereon. In order to adapt the reel 13 to fit the roll having a restricted opening, not shown, the rods 21 are removed from the bars 17 and applied to the inner openings 20 thereof to reduce the diameter of the reel 13.

Various modifications and changes are contemplated and may obviously be resorted to as only a preferred embodiment of the invention has been disclosed.

I claim as my invention:

1. A reel comprising a shaft fixed to a vehicle and having a free end extending beyond an end thereof, a hub rotatably and removably mounted on said free end of said shaft, said hub having an annular flange, a plurality of bars each secured at one of its ends to said flange and projecting radially therefrom, said bars having correspondingly disposed longitudinally spaced apertures adjacent their secured ends, a plurality

of rods each having a threaded end for selectively engaging either of said apertures of one of the bars, a pair of nuts mounted on the threaded ends of each of the rods for clamping the rods to the bars, said rods having opposite, outwardly curved ends extending toward the opposite, secured end of the shaft.

2. A reel comprising a stationary shaft having a secured end and a free end, a hub rotatably and removably mounted on the free end of the shaft, a plurality of bars secured to and projecting radially from the hub and forming one end of the reel, means for clamping the corresponding ends of a plurality of rods to the bars, said bars having longitudinally spaced openings for selectively receiving the rods for adjusting the positions of the rods longitudinally of the bars for varying the diameter of the reel, said rods being disposed transversely to the bars and extending therefrom in the same direction and toward the secured end of the shaft, and said rods having outwardly curved free ends forming the opposite end of the reel.

3. A device as in claim 2, comprising a handle detachably connected to the outer end of one of the bars and extending transversely therefrom in the opposite direction to the rods, said handle forming with said bar a crank for revolving the reel.

RUDOLPH PRANG.
